[57] CLAIM

The ornamental design for a brake pad for a bicycle, as shown.

DESCRIPTION

FIG. 1 is a top view of a brake pad for a bicycle showing my new design;

FIG. 2 is a bottom view of the brake pad as depicted in FIG. 1;

FIG. 3 is a right side view of the brake pad as depicted in FIG. 1 looking into the concave surface of the pad;

FIG. 4 is a left side view of the brake pad as depicted in FIG. 1 looking into the convex surface of the pad;

FIG. 5 is a rear view of the brake pad as depicted in FIG. 1; and,

FIG. 6 is a front view of the brake pad as depicted in FIG. 1.
